UNITED STATES PATENT OFFICE.

ANDREW B. LIPSEY, OF WEST HOBOKEN, NEW JERSEY, ASSIGNOR TO
WILLIAM BELL, OF NEW YORK, N. Y.

GAS-BURNER.

SPECIFICATION forming part of Letters Patent No. 312,279, dated February 17, 1885.

Application filed October 16, 1883. (No model.)

To all whom it may concern:

Be it known that I, ANDREW B. LIPSEY, of West Hoboken, in the county of Hudson and State of New Jersey, have invented a certain 5 new and useful Improvement in Burners for Illuminating Purposes, of which the following is a specification.

The object of my present improvement is to provide a burner which can be made small and 10 neat in appearance, and yet will produce a large and brilliant flame.

I will describe a burner in detail, and then point out the improvement in the claim.

In the accompanying drawings, Figure 1 is 15 a central vertical section of a gas-burner embodying my improvement. Fig. 2 is an inverted view of certain parts located below the dotted line x x , Fig. 1. Fig. 3 is a central vertical section of a gas-burner of modified 20 form embodying the improvement, and Fig. 4 is a section thereof taken near the bottom.

Similar letters of reference designate corresponding parts in all the figures.

Referring first to Figs. 1 and 2, A designates 25 a gas-chamber. As shown, it is of annular form, and is composed of an outer circular shell, a , forming the outer wall, a ring-shaped portion, a' , made integral with the shell a and forming the bottom, and a ring-shaped top 30 plate, a^2 , screwed into the shell a . The shell a is provided with tapped holes a^3 , into which are to be screwed pipes, whereby gas is conducted to the gas-chamber.

From the ring-shaped bottom portion, a' , of 35 the gas-chamber a circular shell, b , extends downwardly. As shown, this shell b is made integral with the bottom portion of the gas-chamber. A shell, b' , is screwed inside the top plate, a^2 , of the gas-chamber, and extends 40 downwardly therefrom within and below the shell b . Between the shells b and b' is a narrower open space in communication at the upper end with the gas-chamber. These two shells therefore form an annular gas-pas- 45 sage, B.

Onto the exterior of the shell b' is screwed 50 a ring, C, provided with a number of outwardly-extending hollow arms, c . On the top of this ring is a V-shaped rib, c' , that enters a

lower edge of the shell b . In this way a tight joint is formed between the two parts when the ring C is screwed up, so that the rib is forced into the groove. The ring C has formed with it a shell, c^2 , which is shouldered between 55 the ends, and has screwed onto its exterior, near its shoulder, a shell, d , that, in conjunction therewith, forms an annular gas-burner tip, D. Passages d' are formed in the shell c^2 between the arms c and the interior of the 60 burner-tip D.

Below the ring C a shell, E, is screwed onto the shell b' . This is made quite thin, and is strengthened by ribs e . It slightly flares toward the lower end. At the lower end a ring, 65 f , secures to it a shell, F, of porcelain, asbestos, or other white material that will become luminous when heated. The ring f has a rib that extends under the inwardly-turned upper edge of the shell F, and this ring is detachably fastened to ribs e by means of L-shaped slots with which it is provided engaging with pins extending from the ribs, like a bayonet-lock. The shell F extends below 70 the burner-tip D a distance approximately 75 equal to the flame which the burner-tip is adapted to produce.

Above the shell b' a shell, b^2 , is screwed into the top plate, a^2 , of the gas-chamber.

G designates a ring which is screwed on the 80 exterior of the ring C, and is provided with hollow arms g , that extend outwardly therefrom. A ring, g' , and shell g^2 are arranged at the outer ends of the arms, and the shell extends downwardly therefrom. A shell, g^3 , 85 screwed onto the ring g' , so as to extend downwardly therefrom, forms, in conjunction with the shell g^2 , an annular gas-burner tip, H.

The burner-tip H is arranged below the burner-tip D a distance approximately equal 90 to the length of the flame intended to be produced by the burner-tip H, thereby forming, in conjunction with the flame from the burner-tip D, one long flame approximately equal to the lengths of the two flames.

Between the burner-tips D and H a shell, 95 h , extends downwardly. It increases in size diametrically to a point a short distance below the burner-tip H, and beyond this point it is provided externally with an external shell 100

of porcelain, asbestos, or analogous material, I. At the extreme lower end it extends toward the burner-tip D.

All the parts described, except those said to be made of porcelain, asbestos, or analogous material, may be made of cast metal, such as iron or brass.

J designates a shell of sheet metal held by friction or by screws or other means upon the exterior of the gas-chamber A. It extends downwardly to a point below the burner-tip H, and is bent inwardly at the lower end. This shell is provided with numerous perforations, i, through which air enters it. Outside the perforations a sheet-metal petticoat, K, is arranged to prevent gusts of air affecting the flames from the burners. This petticoat is hung on the annular gas-chamber, as here shown.

To the shell J is connected, by a hinge, j, and catch k, a globe-holder, L, which may be of ordinary or other suitable construction. The globe M, which is supported by it, is made of glass. Gas passes from the annular gas-chamber to the burner-tips, and air, entering the perforations of the shell J, passes down to the lower ends of the burner-tips, both to the outer sides and to the inner sides, between the arms e g. The products of combustion pass around into the shell F, and thence through the shells E b' b² to the external atmosphere. The gas and air are heated before arriving at the point of combustion. The flames are produced in such positions as to represent the appearance of one long flame. Turning now to

Fig. 3, D and H designate two annular burner-tips arranged in similar relations to each other, as those in the example of my improvement previously described, except that the burner-tips are arranged for use in upright positions, and the burner-tip H is arranged below instead of above the burner-tip D. The arms e, which conduct gas to the passages d' of the shell e', here extend from a socket, A², adapted to be attached to the nipple of an ordinary gas-fixture. The ring G is screwed onto a ring at the outer ends of these arms. Otherwise the burner-tips, and also the shells h and I, are like those before described.

A' designates a pipe extending from the socket A² to a ring, a', forming the bottom of a gas-chamber, A. The shell of this gas-chamber is screwed onto this ring a', and is connected at the top by a plate, a², with small pipes A³, that extend outward, then downward, and then inward to the ring a'. The pipes A³ are merely slipped into the ring a' and plate a²; but the plate a² is screwed upon the upper end of the shell of the gas-chamber. The gas passes from the socket A² along

the pipe A' to the chamber A, thence through the pipes A³ to the ring a', and thence between the pipe A' and the shell E to the arms e, whence it passes to the burner-tips. The shell E is screwed into the ring a', and at the lower end bears upon a ring which is located at the inner ends of the arms e, and formed integral with them. The shell F is here supported above the burner-tip D upon a shoulder extending from the shell E. The shell J here forms a mere deflector, air being admitted through perforations i in the shade or chimney holder L, just inward of this shell, and also through other similar perforations arranged in the holder opposite the spaces between the arms e, and also opposite the spaces between the arms g.

The shade or chimney M may be made of glass, and is shown as of cylindric form.

Hung on the pipes A³ is a metal shell, O, which in effect forms a continuation of the shade or chimney.

In either example of my invention a circular series of burner-tips may be substituted for the annular burner-tips shown.

The shells E, F, h, I, and J in both examples of my invention constitute deflectors, which cause the air to impinge on both the inner and the outer sides of the flames issuing from the burner-tips.

I am aware that concentric burner tubes or jets have been arranged with one elongated above the other and having deflectors between them, and I do not broadly claim such construction.

What I claim as my invention, and desire to secure by Letters Patent, is—

In a burner, the combination of two annular burner-tips or circular series of burner-tips, arranged in such manner that the inner burner-tip or series of burner-tips shall extend beyond the outer burner-tip or series of burner-tips a distance approximately corresponding to the length of the flame intended to be produced by the outer burner-tip or series of burner-tips, thereby forming one long flame approximate in length to the lengths of the two flames, and a deflector whose sides diverge, arranged between the burner-tip or series of burner-tips, so constructed that it will direct air and cause it to impinge against the inner side of the flame from the outer burner-tip or series of burner-tips and the outer side of the flame from the inner burner-tip or series of burner-tips, substantially as specified.

A. B. LIPSEY.
